Specification of Letters Patent.

Patented Mar. 2, 1915.

Application filed April 28, 1910, Serial No. 558,134. Renewed May 20, 1912. Serial No. 698,622.

To all whom it may concern:

Be it known that I, CHARLES G. ASHLEY, a citizen of the United States of America, and a resident of Chicago, county of Cook, 5 and State of Illinois, have invented a new and useful Improvement in Rapid Printing- Telegraph Systems, of which the following is a specification.

My invention pertains to rapid printing 10 telegraph systems and embodies an improvement in transmitting apparatus and circuits as used in such systems. In such systems, a comparatively small number of printing types or equivalent devices are electromagnetically controlled and operated to produce 15 complete characters; each of such types representing one or more component parts or elements of the letters or figures, each letter or figure being produced on a recording 20 tape by printing in proper relation a plurality of the small number of component types representing the respective component parts of the complete characters. In such 25 systems there is employed, as a means of transmitting the current impulses necessary 30 to the operation of the printing types at the receiver, a perforated transmitting tape, the perforations being spaced in a predetermined manner, longitudinally along the tape 35 in order that the types at the receiving station may operate in proper time intervals to accomplish the proper spacing of the printing type elements and complete characters, the transverse spacing of the perforations in the tape permitting the selection of 40 the proper type components to produce the complete character on the recording tape.

The improvement contemplated by my present invention comprises a means where- 45 by the perforations in the transmitting tape may be spaced to operate the transmitting tape at a slow speed compared with the associated transmission speed. I am able to produce a short transmitting tape to trans- mit any given message thus accomplishing a positive and uniform control of the transmitter and to attain a high operating efficiency of the transmitter.

In the drawings which accompany and 50 form a part of this specification—Figure 1 illustrates in diagram the circuit arrangements at both a transmitting and receiving station, together with the line conductors connecting them; Fig. 2 illustrates an end

view of the transmitting device, showing 55 both the tape drums and impulse selector; Fig. 3 is an elevation of the apparatus shown in Fig. 2; Fig. 4 illustrates a section of transmission tape as used with my improved device; Fig. 5 illustrates an arrangement of the type elements or printing faces of the receiving device; Fig. 6 illustrates in diagram the receiver; Fig. 7 illustrates a section of transmitting tape of ordinary form; and, Fig. 8 illustrates a section of recording tape printed with the letters corresponding to perforations in the section of transmitting tape shown in Figs. 4 and 7.

Referring to Fig. 1, conductors 40 and 41 are the transmitting line conductors; 70 at the left are the transmitting devices; and at the right are the receiving devices, shown in diagram in order to make clear the electrical circuits. Electrically considered, the object of the system of Fig. 1 is to control 75 selectively the operation of the printing pens 20', 20², 20³, and 20⁴ of the receiving device 20, by means of circuits closed through holes punched in the transmitting tape 11, the controlling circuit being formed 80 over the conductors 40 or 41 and ground, the actuating electromotive force being supplied by the direct current generators 2 and 3, and the polarity of the actuating currents being controlled by the selecting device 5.

Describing first the receiving devices in order that the requirements of the transmitting devices may be more fully understood, reference is made to Figs. 5 and 6, as well as to Fig. 1, in all of which like reference numerals denote like parts. The printing types 20', 20², 20³ and 20⁴ are carried on springs and are normally held against the tension of these springs out of contact with the recording tape 21 through the influence 95 of the polarizing magnet 26. Four electromagnets, as 31 and 32, are associated each with one of the printing pens, the windings of the magnets controlling the pens 20' and 20², being placed in series each to each and 100 connected to one of the line conductors and the ground, while the windings of the magnets controlling pens 20³ and 20⁴ are placed in series each to each and connected to the other line conductor and the ground. The 105 winding of each pair of magnets so placed in the circuit is arranged so that an impulse of one polarity will release one pen of that

pair of pens and allow it to make an imprint on the recording tape 21, while the other pen of the pair will be more strongly attracted to its controlling magnet. An anvil 24 is placed opposite the printing face of the pen. The recording tape 21 lies upon the surface of the anvil and is passed laterally before the printing face of the pen by means of rollers 22 and 23. The receiver illustrated is arranged for electro-chemical printing and a battery 25 is connected to the pens and the anvil for that purpose. This means of printing is common in the art and needs no further explanation.

15 The transmitting device, together with its associated circuits, embodies the improvement of my present invention. This device, as illustrated in Figs. 1, 2 and 3, comprises a continuously revolving drum 10, carrying 20 five conductor rings $7'$, 7^2 , 7^3 , 7^4 and 7^5 , each moving in continuous contact with one of the five brushes $10'$, 10^2 , 10^3 , 10^4 and 10^5 , respectively. Brush 12 is adapted to make contact with three of the rings, as $7'$, 7^2 , 7^3 , 25 while brush 13 is adapted to make contact with rings 7^4 and 7^5 . Brushes 12 and 13 are, however, normally held out of contact with the conductor rings by the perforated transmitting tape 11. An impulse selector 30 5, comprising a series of insulated contacts $5'$, 5^2 , 5^3 , 5^4 ; $15'$, 15^2 , 15^3 , 15^4 , is mounted rigidly upon the frame of the transmitter and provided with a contact maker 15 carried upon the shaft 8 and rotated with the 35 drum 10 by means of the spur gears 14 and 17, thus always maintaining a definite relation between the position of the contact maker 15 and drum 10. The contacts $5'$ to 5^4 of the impulse selector 5 are connected to the brushes $10'$ to 10^5 as follows: Contact $5'$ is connected to brush $10'$; contact 5^2 to brush 10^2 ; contact 5^3 to brush 10^3 ; and contact 5^4 to brushes 10^3 and 10^4 . Contacts $15'$ and 15^3 are connected to the negative terminal of generator 3, while contacts 15^2 and 15^4 are connected to the positive terminal of generator 2. The generators have their remaining terminals connected together and grounded at 1. Wiper 15 of the impulse selector, as viewed in Fig. 2, is adapted to rotate from left to right and to make contact simultaneously between the insulated contacts 5^4 and 15^4 ; 5^3 and 15^3 , etc., thus placing a current impulse of predetermined polarity upon the brushes 10^5 , 10^4 and 10^3 , etc. The transmitter drum 10 is provided with a central row of pins 9, spaced at equal distances along the surface of the drum and adapted, through a series of central perforations in the transmitting tape 11, to maintain the tape in a predetermined register with the surface of the drum during the longitudinal motion of the tape through the transmitter. The transmitting tape, through perforations therein, permits

contact between the brushes 12 and 13 and their associated conductor rings, and therefore through impulse selector 5 with grounded generators 2 or 3. This contact is selective in two functions: First, in selecting the proper conducting ring, and second, in selecting the proper instant with reference to contacts made previously or to be made subsequently. A time relation exists between the speed of the transmitting tape 70 and the speed of the wiper 15 of impulse selector 5, which permits of the selection of proper polarity of the impulse. A time relation also exists between the speed of the transmitting tape, impulse selector and recording tape, in order that the printed components of the letters or numerals may be promptly spaced, and further, in order that the letters or numerals may be correctly spaced on the recording tape. 80

The recording tape, as well as the transmitting tape, is moved longitudinally in any well-known manner. I prefer, however, to employ small electric motor-driving rollers which serve to pull the tape at a 90 uniform and proper speed through the receiving device, and allow the transmitting tape to be carried through the transmitter by means of the pins on the drum, the power being derived from a small electric sector, 95 through the shaft 8.

Control of the printing pens 20' to 20⁴ by perforations in the tape 11 is as follows: Perforations in the tape are confined to five longitudinal rows corresponding to the five contact rings $7'$ to 7^5 of the transmitter drum 10 and numbered 1, 2, 2', 4, 3. The row of central perforations 11' in the tape 11 are spaced to register with and admit the prongs 9 on the drum 10, the spacing of the 105 prongs being in such relation with the speed of the drum 10 and wiper 15 as to allow of wiper 15 making one-half revolution, while that portion of the circumference of the drum 10 defined between any two prongs is 110 passing under the contact portion of brushes 12 and 13. Thus, by proper spacing of the perforations between any two central perforations of the tape 11, a positive and negative impulse may be sent over either 115 line through its associated pair of receiving magnets to operate pens, as 20' and 20², and the ground 51. Any perforation placed in the tape along the line 1 of the tape and opposite any central perforation, will always allow of the pen 20' being operated to imprint its component of a letter or numeral. Any perforation spaced along the line 2 of the tape 11 and on a line connecting line 1 and line 3 of tape 11, will allow 120 of an impulse of opposite polarity from the initial impulse to be sent over the same line through the same pair of receiving magnets, and will cause the operation of the pen 20², thus imprinting the character rep. 125 130

resented thereby on the receiving tape. A perforation spaced along the line 4 of the tape 11 and on a diagonal line connecting line 3 and line 1 of the tape, will allow an impulse of predetermined polarity to be sent over the other line to ground, thus operating pen 20⁴, while a perforation spaced along the lines 2' and 3 of tape 11 will, as hereinafter described, allow pens 20² or pen 20³ to be operated. As viewed in Figs. 2 and 3, the selector is in a position to impress a positive impulse upon rings 7² and 7⁴, allowing, through perforations in tape 11, an impulse to be sent over either line to ground, dependent upon whether the perforation is spaced along line 2' or 4 of the tape 11, thus operating either pens 20² or 20⁴, as the case may be. Considering tape 11 to move from right to left with relation to the brushes 12 and 13, a distance equal to one-fourth the distance between any two central perforations, as 11', the wiper 15 of selector 5 will rotate, the shaft 8 rotating from left to right, and move from making contact between contacts 5⁴ and 15⁴ to making contact between contacts 5² and 15², thereby removing positive polarity from rings 7² and 7⁴ and placing negative polarity on ring 7⁵, allowing thereby, through a perforation along line 3 of tape 11, the operation of pen 20³. In the same manner, while wiper 15 is making one-half revolution, by proper spacing both longitudinally and transversely of the perforations in the tape 11, a positive and negative impulse may be sent over either line 40 or 41 and the ground. The instant between any two impulses will be called a time interval or tape interval, and as described, four of these time intervals will exist between any two central perforations of the tape 11.

The size of the perforations in the transmitting tape should be such that the brushes make contact with the collector rings before the current is placed on the collector rings in question, and that the current be removed from the ring in question before the contact between the brush and collector ring is broken by the tape. This tends to insure a positive contact at the time the current is applied and removed, thus resulting in a positive operation of the printing pens, and also eliminates the danger of burning the tape at the edges of the perforations.

Fig. 5 shows the arrangement of the printing faces of the pens 20¹ to 20⁴, the imprints being shown as printed on a stationary receiving surface, or as though all four pens are printed simultaneously upon a moving surface. Four tape intervals are considered equal to the length of the element 20² and one tape interval is equal to the longitudinal spacing of the elements. Pen 20¹ is controlled through perforations in tape 11, spaced longitudinally along line 1. Pen 20²

is controlled through perforations along either line 2 or 2' of tape 11. Pens 20³ and 20⁴ are controlled through perforations along lines 3 and 4, respectively, in tape 11. The method of combining these individual imprints of the pens to produce a desired character is as follows: Referring to Figs. 4, 5 and 8, the tape is perforated to transmit the letters A, O and E. Considering the recording tape (Fig. 8) to pass laterally from right to left under the type faces of Fig. 5 while the transmitting tape is passing under the brushes 12 and 13 of Fig. 2 from right to left, the letter A is produced by first imprinting pen 20⁴, then after four time intervals imprinting 20⁴ again, and after a lapse of two time intervals imprinting type 20², and again after a lapse of one time interval imprinting type 20¹, thereby imprinting upon the recording tape the character A. The letter O is printed as follows: The pen 20⁴ is first imprinted, and after a lapse of four time intervals the pen 20⁴ is again imprinted. After a lapse of one time interval the pen 20³ is imprinted; however, this pen is not influenced through a perforation along line 2' of tape 11, as reference to Fig. 1 will show that pen 20³ is connected to line conductor 41. Therefore, the perforation is placed along line 3 of tape 11 and in a line with the position it should occupy along line 2' of tape 11 to be in proper time relation with the previous imprint. Following this imprint after a lapse of two time intervals, the pen 20¹ is imprinted, thereby producing the character O. Character E is imprinted as follows: Pen 20⁴ is first imprinted; then, after a lapse of four time intervals pen 20² is imprinted as follows—at the instant when it is desired to imprint 20² brushes 10³ and 10⁴ are connected with a positive potential, as wiper 15 of contact maker 5 is at this instant making contact through the contact 5⁴ and 15⁴ with the positive lead of the generator 2. Thus, a positive impulse may be sent through brush 10⁴ to line 41, or through brush 10³ to line 40. As a positive impulse over line 40 is necessary to operate pen 20², the perforation in the tape 11 is spaced along line 2' of tape 11 and directly opposite the position it should occupy along line 4' of tape 11 in order to be in the fourth tape interval. After imprinting the pen 20², a lapse of one time interval, and pen 20³ is imprinted, as has been explained in the foregoing description of the printing of character O. Then, after a lapse of two time intervals the pen 20¹ is imprinted, thereby producing the character E.

The spacing of the letters on the recording tape, as shown, is accomplished by allowing four tape intervals between the punchings for each letter on the transmitting tape, as shown.

It will be observed from the foregoing that in order to produce a letter or numeral it is only necessary to imprint the proper predetermined pens with a proper predetermined number of time units or intervals between the instants of printing, the number of time units being dependent upon the result desired.

The speed of the transmitting tape, ¹⁰ pulse selector and receiving tape is such as to move the transmitting tape one tape interval in the time required to produce the proper distance unit upon the recording tape. This requirement merely places a required ¹⁵ ratio upon the speed of the transmitter and receiver, and this ratio may be adjusted after an inspection of the work done.

In Fig. 7, I have shown a section of transmitting tape of common form. In this tape ²⁰ the four positions for perforations upon the tape are shown by the lines 1, 2, 3 and 4, the perforations being positioned in the tape at transverse positions corresponding to each of these lines, producing upon the recording ²⁵ tape impressions of the correspondingly numbered pens, and the longitudinal positions of the imprints upon the recording tape are determined wholly by the longitudinal position of the perforations in the ³⁰ transmitting tape. In this system the unit of time between impulses is represented by the transverse dotted lines, from which it is clearly seen—on comparing this tape with the tape of my improved device shown in ³⁵ Fig. 4, that the tape used in my improved device is about one-quarter that necessary for the same letter in the tape of Fig. 7.

The record on the recording tape—Fig. 8—is as shown when either transmitting ⁴⁰ tape is used in their respective systems.

It will be observed that a constant angular relation is maintained through the gears 14 and 17 between the wiper 15 and the drum 10, and as this relation is such as to allow of four impulses being selectively placed upon the brushes 10' to 10° during the angular rotation of the drum 10 through a distance represented by that between any two pins on the circumference of the drum, ⁴⁵ that it is only necessary in a perforated message tape to provide that the first tape interval, whether perforated to send an impulse to imprint the pen 20' or not, shall always fall opposite one of the central perforations in the tape. When the tape is so perforated ⁵⁰ with any message, it may be placed on the drum so that its central perforations register with the prongs on the surface of the drum, and if the perforations have been properly spaced both longitudinally and transversely, the message will be automatically recorded at the receiving end of the line.

While I have illustrated and described my ⁶⁵ device in connection with two direct current

generators as a source of supply, it is obvious that I may utilize any other well-known source of supply. Further, it is obvious that while I have shown a particular design of device, many modifications may be made therein without departing from the spirit or narrowing the scope of my invention.

Having thus described my invention, what I claim as new and desire to secure by ⁷⁰ United States Letters Patent is:

1. In a system of printing telegraphy, a transmitter; a receiver; and conductors connecting same; said transmitter comprising a plurality of insulated conducting members; means for impressing upon said conducting members in predetermined sequence and at predetermined time intervals current impulses of predetermined polarity, and means for selectively transferring said current impulses to said conductors.

2. In a system of printing telegraphy, a transmitter; a receiver, and conductors connecting same, said transmitter comprising a plurality of insulated conducting members; means for impressing upon said conducting members in predetermined sequence and at predetermined time intervals current impulses of predetermined polarity and duration; collecting members bearing upon ⁹⁰ said conducting members and adapted to transfer said impulses selectively to said conductors.

3. In a system of printing telegraphy, a transmitter; a receiver; and a pair of line wires and ground connecting same, said transmitter comprising a plurality of insulated conducting members; a plurality of collecting members bearing upon said conducting members; a source of current; and means whereby impulses from said source, of predetermined polarity and duration, may be placed through said collecting means upon said conducting means in a predetermined sequence and thence may be selectively placed on either of said lines and the ground.

4. In a system of printing telegraphy, a transmitter; a receiver; line conductors and ground connecting same; said transmitter comprising a plurality of conducting members; means for impressing upon said conducting members in predetermined sequence and at predetermined time intervals current impulses of predetermined polarity and duration; and means for selectively transferring said current impulses in a predetermined sequence to either of said line conductors and ground; the duration of said impulses on such transfer depending wholly upon the impressing means.

5. In a system of printing telegraphy, a transmitter; a receiver; line conductors and ground connecting same; said transmitter comprising a plurality of conducting mem-

bers; collecting members bearing upon said conducting members; transfer members bearing upon said conducting members and connected to said line conductors; a source of current; means whereby current impulses from said source, of predetermined polarity and duration, may be placed in a predetermined sequence at predetermined time intervals through said collective members on said conducting members; and means whereby said impulses may be placed upon either of said lines and ground through said transfer members.

6. In a system of printing telegraphy, a transmitter; a receiver; line conductors and ground connecting same; said transmitter comprising a plurality of conducting members; collecting members upon said conducting members; transfer members bearing upon said conducting members and connected to said line conductors; a source of current; means whereby current impulses from said source, of predetermined polarity and duration, may be placed in a predetermined sequence through said collecting members on said conducting members; a tape between said conducting members and said transfer members and adapted through perforations therein to allow of selection and predetermination of the impulses which are placed over either of said line conductors and the ground.

7. In a system of telegraphy, a transmitter; a receiver; line conductors and ground connecting same; said transmitter comprising a plurality of conducting members; collecting members upon said conducting members; transfer means bearing upon said conducting members, and connected to said line conductors; a source of current; means whereby current impulses from said source of predetermined polarity and duration may be placed in a predetermined sequence through said collecting members on said conducting members; a tape between said conducting members and said transfer members and adapted through perforations therein to allow of selection and predetermination of the impulses which are placed over either of said line conductors and the ground; the duration of said impulses being determined wholly by said impulse impressing means.

8. In a system for the communication of intelligence, a transmitter; a receiver; line conductors and ground connecting same; said transmitter comprising a plurality of insulated conducting rings; a plurality of brushes bearing upon said rings; a source of current; an impulse selector connected to said source and adapted to transmit current impulses of predetermined polarity and duration through said brushes to said conducting rings; a pair of brushes, one of each connected to one of each of said line conductors and bearing upon said conducting

rings; a tape between said pair of brushes and said rings, and adapted through perforations therein to permit said pair of brushes to make contact with said rings in a predetermined sequence.

9. In a system for the communication of intelligence, a transmitter; a receiver; line conductors and ground connecting same; said transmitter comprising a plurality of insulated conducting rings; a plurality of brushes bearing upon said rings; a source of current; an impulse selector connected to said source and adapted to transmit current impulses of predetermined polarity and duration through said brushes to said conducting rings; a pair of brushes, one of each connected to one of each of said line conductors, and bearing upon said conducting rings; a tape between said pair of brushes and said rings and adapted through perforations therein to permit said pair of brushes to make contact with said rings in a predetermined sequence, the interval of connection between any ring and any brush through any perforation in said tape being always greater than the duration of the current impulse with which the ring is enlivened.

10. In a printing telegraph system, depending for its operation upon the sending in proper sequence of electrical impulses over a line; a transmitter; a perforated tape for determining the sequence of the impulses sent by said transmitter, the perforations of said tape being arranged in transverse rows, the longitudinal movement of the tape determining the timing of the group of impulses represented by a transverse row; and a device associated with said transmitter for determining the sequence of the impulses represented by the perforations in a transverse row.

11. In a printing telegraph system, depending for its operation upon the sending of electrical impulses over a line in proper kind and sequence; a transmitter; a perforated tape for determining the kind of sequence of impulses sent by said transmitter, the perforations of said tape being arranged in transverse rows; means whereby the position of said perforations in said rows determines the kind of impulse to be sent; and a device associated with said transmitter for determining the sequence of the impulses represented by the perforations in a transverse row.

12. In a printing telegraph system of the kind wherein characters are formed by sending electrical impulses in proper sequence over a line; a transmitter; a perforated tape for determining the sequence of the impulse sent by said transmitter, the perforations of said tape being arranged in transverse rows across said tape; a contact device co-operating with the perforations in said tape;

- means for imparting a longitudinal movement to said tape for causing the engagement of said contact device successively with said transverse rows of perforations; and a 5 device associated with said transmitter for determining the sequence of the impulses represented by the perforations in a transverse row.
13. In a system of printing telegraphy, 10 a transmitter, a receiver, and conductors connecting same, said transmitter comprising a plurality of insulated conducting members, means for impressing upon said conducting members in predetermined sequence and at predetermined time intervals current impulses of predetermined polarity and duration, and means for selectively transferring said current impulses in predetermined groups to said conductors.
14. In a printing telegraph transmitter, 15 a plurality of insulated conducting members, a source of current, means for impressing on said conducting members in predetermined sequence and a predetermined time intervals current impulses of predetermined polarity and duration from said source and means for selecting predetermined groups of said impulses for transmission purposes.
15. In a printing telegraph system depending for its operation upon the transmission in proper sequence of electrical current impulses a perforated tape, a commutating device coacting with said tape for predetermined the sequence and duration of predetermined groups of said impulses thereon and the rows being substantially transverse with respect to the longitudinal dimension of the tape.
16. The combination with devices for producing an alternating current independently of a perforated tape, a line over which such current may flow, and means controlled by said devices for permitting only predetermined impulses to flow over said line, of 45 two magnets connected in series to said line, said magnets being operated individually by impulses of opposite polarity, and printing characters actuated by said magnets.
17. Devices for producing an alternating current, a line over which such current flows, two polarized magnets connected in series to said line and operated alternately by the 55 alternations of the current, circuit making and breaking devices for connecting the current to and disconnecting it from the line, and automatically operating means for caus-
- ing irregular operations of the circuit making and breaking devices to come in predetermined relationship to the alternations of the current.
18. The combination with a contact closing device, means independent of a perforated tape for impressing an alternating current upon one element of said device, and a line connected to the other element, of a perforated sheet normally separating the elements of said device, means for moving the sheet so that perforations therein will permit the device to close in definite relationship to the alternations of the current, and two magnets connected to the line and operated independently by impulses flowing therethrough.
19. The combination with devices for producing an alternating current independently of a perforated tape, a line over which such current may flow, and two magnets connected to the line and operative alternately by the alternations of the current, of means for intercepting desired alternations so as to exclude the same from said magnets.
20. The combination with a plurality of contact closing devices, means independent of a perforated tape for impressing the impulses of an alternating current upon one element of each device, a line connected to the other element of each device, and two magnets in each line, the magnets of each line being of opposite polarity, of means for normally holding the contact devices open, and means for permitting the contact devices to close selectively so as to cause any desired succession of operations of the magnets on said lines.
21. The combination with a source of alternating current independent of the use of a perforated tape, two lines over which such current may simultaneously flow, and two magnets connected to each line, one magnet on each line being operated by current in one direction and the other magnet on each line being operated by current in the reverse direction, of means for intercepting desired alternations on the lines independently so as to cause said magnets to operate in any desired succession.

Correction in Letters Patent No. 1,130,688.

It is hereby certified that in Letters Patent No. 1,130,688, granted March 2, 1915, upon the application of Charles G. Ashlev, of Chicago, Illinois, for an improvement in "Rapid Printing-Telegraph Systems," an error appears in the printed specification requiring correction as follows: Page 5, line 112, for the word "of" read *and*; and that the said Letters Patent should be read with this correction therein that the same may conform to the record of the case in the Patent Office.

Signed and sealed this 23rd day of March, A. D., 1915.

[SEAL.]

J. T. NEWTON,

Acting Commissioner of Patents.
